UNITED STATES PATENT OFFICE.

ALBERT A. GORDON, JR., OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DOBBY PATTERN-CYLINDER.

1,145,677.

Specification of Letters Patent.

Patented July 6, 1915.

Application filed March 25, 1914. Serial No. 827,226.

To all whom it may concern:

Be it known that I, ALBERT A. GORDON, Jr., a citizen of the United States, residing at Worcester, in the county of Worcester 5 and State of Massachusetts, have invented a new and useful Dobby Pattern-Cylinder, of which the following is a specification.

This invention relates to a doby pattern cylinder and particularly to improved means 10 for positioning and driving pattern chains supported thereon.

It is the principal object of my invention to provide a doby pattern cylinder which is equally adapted to drive chains formed 15 of full length bars and chains formed of short-length bars.

With this object in view, my invention consists in the provision of a circumferentially adjustable member mounted upon the 20 hub of the pattern cylinder and adapted, when in one position, to coöperate with and drive chains composed of full length bars and, when in another position, to coöperate with and longitudinally position chains composed of short-length bars.

My invention further consists in certain devices, arrangements and combinations of parts which will be hereinafter described and more specifically pointed out in the appended claims.

A preferred form of the invention is shown in the drawings in which—

Figure 1 shows a portion of a doby with the pattern cylinder shown in section and in 35 its operative position; Fig. 2 is a side elevation of the pattern cylinder, the parts being adjusted to coöperate with chains having short length bars; Fig. 3 is a section taken along the line 3—3 of Fig. 2; Fig. 4 is a side elevation similar to Fig. 2 but having the parts arranged to coöperate with a chain composed of full length bars; Fig. 5 is a section taken along the line 5—5 of Fig. 4, and Fig. 6 is a detail view of the adjustable 40 member.

In Fig. 1 of the drawings the numeral 10 indicates a portion of a doby frame upon which are pivotally supported a plurality of indicating fingers 11 and 12. These fingers 50 are mounted to turn upon the transverse cylindrical bar 13 and are held in position thereon by a transverse rod 14. The fingers 11 coöperate with lifter rods 15 through which the upper hooks of the doby (not 55 shown) are controlled. The fingers 12 are

up-turned at their operative ends and co-operate directly with the lower hooks of the doby (not shown). The pattern cylinder 16 is mounted in the frame 10 to rotate beneath the indicating fingers and serves to 60 move the bars 17 of the pattern chain intermittently under the fingers 11 and 12. These bars are provided with projecting studs 18 which lift the indicating fingers and thus control the hooks of the doby.

The mechanism thus far described is of the usual form and constitutes no part of my present invention.

In the operation of a doby of this type it is sometimes desirable to use a pattern 70 chain formed of full length bars such as are shown at 19 in Fig. 4 and at other times it is desirable to use two chains each composed of short-length bars such as are shown at 20 in Fig. 2.

My present invention relates to means for adapting a single pattern cylinder so that it may position and operate chains of either type.

My improved pattern cylinder comprises 80 a hub 21 having a flange 22 at each end and having two separated sets of projections 23 intermediate said flanges. The inner face of each flange is beveled to correspond with the bevel on the end of the pattern chain 85 bars and the flanges thus serve to position the bars longitudinally upon the cylinder.

It will be evident from inspection of Fig. 4 that the bars 19 extend the full length of the cylinder between the two flanges 22 and 90 that any obstruction in the line of the recesses formed between the projections 23 would render the cylinder inoperative for such bars. Inspection of Fig. 2 will also show that when chains composed of short- 95 length bars 20 are in use there is a space between the inner ends of the bars and that provision must necessarily be made to prevent longitudinal movement of the bars away from the flanges 22. In order to provide 100

for these two conditions of operation, I have secured to the hub 21 between the projections 23 a circumferentially adjustable member 24 having a plurality of projection lugs 25 formed thereon. These lugs 25 correspond 105 in transverse section to the transverse section of the projections 23 and they correspond in longitudinal section to the angle of the inner faces of the flanges 22. The member 24 is provided with a slot 26 and is secured 110

2
to the hub 21 by a screw 27 passing through said slot. For convenience of manufacture the member 24 is usually formed in two semi-circular parts, each part being provided with a slot and screw connection for adjustably securing it to the hub. When it is desired to use the cylinder with a chain composed of full length bars, the member 24 is moved to the position shown in Fig. 4 in which the lugs 25 are longitudinally alined with the projections 23. In this position they do not interfere with the bars 19 and furthermore they coöperate with the projections 23 in driving the pattern chain. When it is desired to use chains composed of short-length bars, the member 24 is adjusted in the position shown in Fig. 2 in which the lugs 25 are alined with the recesses between the projections 23. In this position the beveled sides of the lugs 25 coöperate with the beveled inner faces of the flanges 22 to position the pattern chain bars longitudinally.

While I have described my invention as embodied in a dobby pattern cylinder, it is obvious that it may be used in any mechanism in which similar pattern chains are provided. Furthermore it will be evident that many changes and modifications can be made in my invention without departing from the spirit and scope thereof and I do not wish to be limited to the precise details herein disclosed, but

What I do claim is:—

- 35 1. A pattern cylinder comprising separated sets of chain-driving projections, a flange at each end of the cylinder for positioning the pattern chain bars longitudinally, and a member circumferentially adjustable between said sets of projections and effective in one position to coöperate with said projections to drive full length pattern bars and in another position to coöperate with said flanges to longitudinally position short-length pattern bars.
- 40 2. A pattern cylinder comprising a hub, separated sets of chain-driving projections mounted thereon, a flange on each end of

said hub, a member circumferentially adjustable on said hub between said sets of projections and having a plurality of lugs thereon corresponding in transverse section to said projections and in longitudinal section to the inner angle of said flanges, and means to hold said member in adjusted position with said lugs effective to separate full length pattern bars laterally or to separate short length pattern bars longitudinally.

3. A pattern cylinder comprising a hub, separated sets of chain-driving projections mounted thereon, a flange on each end of said hub, and a member circumferentially adjustable on said hub between said sets of projections and having a plurality of lugs thereon corresponding in transverse section to said projections and in longitudinal section to the inner angle of said flanges, said member and said hub having a slot and screw connection effective to hold said lugs in longitudinal alinement with said projections or in alinement with the recesses between said projections as desired.

4. A pattern cylinder comprising a hub, separated sets of chain-driving projections mounted thereon, a flange on each end of said hub, and a member circumferentially adjustable on said hub between said sets of projections and having a plurality of lugs thereon corresponding in transverse section to said projections and in longitudinal section to the inner angle of said flanges, said member comprising a plurality of parts each having a slot and screw connection with said hub effective to hold said lugs in longitudinal alinement with the recesses between said projections as desired.

In testimony whereof I have hereunto set my hand, in the presence of two subscribing witnesses.

ALBERT A. GORDON, JR.
